(57) **CLAIM**

The ornamental design for a wristband with color illuminated members, as shown and described.

DESCRIPTION

The patent or application file contains at least one drawing executed in color. Copies of this patent or patent application with color drawings(s) will be provided by the Office upon request and payment of the necessary fee.

FIG. 1 is a front perspective view of a wristband with color illuminated members showing our new design;

FIG. 2 is a side view thereof; and,

FIG. 3 is a front view thereof.

The broken lines immediately adjacent to the shaded area represent unclaimed boundaries of the design. The broken lines showing the remainder of the wristband are for environmental purposes only and form no part of the claimed design.
